(57) **CLAIM**

The ornamental design for a floating dispenser, as shown and described.

DESCRIPTION

FIG. 1 is a perspective view of a floating dispenser according to the present invention.

FIG. 2 is a side elevational view of the floating dispenser shown in FIG. 1, the dispenser having the same appearance from the front and rear sides.

FIG. 3 is a top elevational view of the floating dispenser shown in FIGS. 1 and 2; and,

FIG. 4 is a bottom view of the floating dispenser shown in FIGS. 1-3.
